US0D1020053S

(12) United States Design Patent (10) Patent No.: US D1,020,053 S
(45) Date of Patent: * Mar. 26, 2024

(54) LAMP

(71) Applicant: Inter IKEA Systems B.V., LN Delft (NL)

(72) Inventor: Henrik Preutz, Älmhult (SE)

(73) Assignee: INTER IKEA SYSTEMS B.V., Delft (NL)

() Term: 15 Years

(21) Appl. No.: 29/848,244

(22) Filed: Aug. 1, 2022

(30) Foreign Application Priority Data

Feb. 4, 2022 (WO) WIPO113196

(51) LOC (14) Cl. 26-05

(52) U.S. Cl.

USPC D26/107; D19/77

(58) Field of Classification Search

USPC ..... D26/24, 51, 60, 61, 62, 63, 65, 93, 94, D26/106, 107, 113, 142; D19/77, 78, 85 CPC F21S 6/00; F21S 6/002; F21S 6/003; F21S 6/004; F21S 6/005; F21S 6/006; F21S 6/008; F21L 4/00; F21L 4/025; F21L 4/027; F21W 2131/00; F21W 2131/30

See application file for complete search history.

Primary Examiner — Samantha Wood

Assistant Examiner — Vanessa Martinez

(74) Attorney, Agent, or Firm — Tucker Ellis LLP

(57) CLAIM

The ornamental design for a lamp, as shown and described.

DESCRIPTION

FIG. 1 is front, right, top perspective view of a lamp in a bent configuration showing my new design;

FIG. 2 is a front perspective view thereof;

FIG. 3 is a rear perspective view thereof;

FIG. 4 is a left side perspective view thereof;

FIG. 5 is a right side perspective view thereof;

FIG. 6 is a top perspective view thereof;

FIG. 7 is a bottom perspective view thereof; and,

FIG. 8 is a front, right, top perspective view of the lamp in a straight configuration.

The broken lines and de-emphasis in FIG. 6 are used to represent portions of the lamp that form no part of the claimed design.

1 Claim, 8 Drawing Sheets
